MACHINE FOR SEPARATING AND SELECTING WARP-THREADS OR THE LIKE.

1,169,087.

Specification of Letters Patent. Patented Jan. 18, 1916.

Application filed September 16, 1908. Serial No. 453,224.

To all whom it may concern:

Be it known that we, EDGAR F. HATHAWAY and CHARLES LEA, both citizens of the United States, and residing, respectively, at Dorchester and Boston, both in the county of Suffolk and State of Massachusetts, have invented an Improvement in Machines for Separating and Selecting Warp-Threads or the like, of which the following description, 10 in connection with the accompanying drawings, is a specification, like letters on the drawings representing like parts.

This invention relates to textile machines and more particularly to machines for operating upon warp threads preparatory to their installation in the loom, such class of machines comprehending warp drawing, warp tying, cementing and twisting machines, as well as other machines requiring 20 the coördinate separation and selection of such successive members of one or more series of loom elements, such, for example, as the eyes of one or more harnesses coördinately with the threads of a new warp and 25 the dents of a loom reed.

While our invention is applicable to textile machines other than those above recited, it has particular application to such machines and, for illustrative purposes, we 30 have shown one embodiment thereof applied to a machine for drawing in warp threads through the heddle eyes of a plurality of harnesses and the dents of a loom reed. It will be understood that such embodiment of our invention is illustrative only and that the same as to certain of its features may have extensive application to other forms of warp drawing machines than the specific one herein shown, as well as to 35 textile machines other than those used for the specific purpose of drawing in warp threads.

Our invention will be best understood by reference to the following description when 40 taken in connection with the accompanying illustration of one specific embodiment thereof, while its scope will be more particularly pointed out in the appended claims.

In the drawings: Figure 1 shows in plan and partially broken away the principal working parts of a warp drawing machine embodying one form of our invention; Fig. 2 shows one end of the machine in rear elevation; Fig. 3 is a similar view of the mid portion of the machine; Fig. 4 is a detail in sectional elevation showing the support for the lower reed bar; Fig. 5 is a view similar to Fig. 3 but showing the next adjacent portion of the machine; Fig. 6 shows the auxiliary head when used in conjunction with short separator shafts extending therethrough; Fig. 7 shows a detail of the auxiliary head when fitted with elongated or extended separator shafts; Fig. 8 is a detail in transverse vertical section showing one of the reed supporting hangers; Fig. 9 is a transverse section showing one of the reed clamps; Fig. 10 is a detail in plan showing the clamp actuating plate; Fig. 11 is a section in elevation showing the clamp actuating lever; Fig. 12 is a detail in plan showing the connection of the lever to the plate; Fig. 13 is a detail in enlarged section, showing the latch for the auxiliary head; Fig. 14 is a detail in elevation showing the stop block for the auxiliary head; and Fig. 15 is an end view of the coupling for the separating shafts.

Referring to the drawings, we have there shown for illustrative purposes one form of our invention embodied in a well-known form of warp-drawing machine, the specific machine shown being intended more particularly for use in conjunction with warps of extra width or extent.

In the illustrated machine there is provided a bed or frame work 1, upon which are appropriately positioned the various loom elements, such as the warp threads 2 (see Fig. 1) harnesses 3 (Fig. 2) and reed 4. These are sustained herein parallel with the length of the machine and so related to the separating, selecting and threading mechanisms that relative traversing movement is provided between the latter and the several sets of loom elements.

While, for this purpose, if desired, the

warp, harness and reed supports might themselves be movable past the threading and selecting mechanism and the latter held fixed, in the present case the various separating and selecting devices are sustained upon a carriage 5, which is mounted to be moved lengthwise the bed 1 by means of the lead screw 6, thereby to move operatively across and traverse the loom elements, 5 which latter are given a relatively small compensating movement only. During the traverse of the carriage, suitable threading mechanism, such as the warp-drawing needle 7, having suitable reciprocating driving mechanism, is caused to draw successive warp threads through the selected harness eyes and reed dents.

In the present machine the selecting and separating mechanisms for the warp threads, harness eyes and reed dents are also supported upon the traversing carriage 5 and caused to move therewith lengthwise the machine. While any suitable selecting and separating devices may be employed, 20 in the present instance we have shown a machine fitted with a warp separating worm or screw 8 of the general type shown in British Patent No. 4661 of 1904, harness separating worm of the type shown in U. S. Patent No. 600,670, and a reed opener 25 10 of the general type shown in U. S. Patent No. 871,680.

In the present machine also, as in the machines of the said prior patents such separating and selecting devices are provided with longitudinally extending actuating members, herein comprising the shaft 11 for the warp worm 8, the shafts 12 (herein four in number) for the harness worms 9, and the reed opener shaft 13 for the reed opener 30 10. These longitudinally extending actuating shafts receive journal support at or adjacent their active ends, the reed shaft in a bracket 14 mounted on the carriage 5, and the remaining shafts in an extension arm 15, also supported by the said carriage and movable therewith. To support as well as drive these shafts at their opposite ends there is provided a second traversing carriage 16 carrying a head 17 on which the ends of the shaft receive journal support and a second head 18, the latter associated with pattern control mechanism, such as the pattern chain 19 and appropriate clutches 35 20 interposed between the pattern chain and the driving mechanism, whereby any of the several operating shafts for the selecting mechanism may be actuated and timed in accordance with a predetermined pattern arrangement to effect the separation and presentation to the needle of the warp threads, harness eyes and reed dents in appropriate order and at appropriate times.

The pattern control mechanism as shown, 40 being well known upon machines of this

class, (disclosed for example as to its main features in the said British Patent No. 4661 of 1904) and our invention not being particularly concerned with the constructional details thereof, no further description of its 70 details need here be given.

The pattern carriage 16 has rigid connection to the traversing carriage 5 as by gib, one of which is shown at 21, so that the two carriages move together carrying the separating mechanism and drawing-in mechanism across the full extent of the warp threads, harnesses and reed.

If the capacity of the machine is increased to permit it to draw extra wide warps, the 80 length of the actuating shafts is apt to become excessive, leaving a long overhand between their supports at the carriage 5 and at the pattern carriage 16. To meet this difficulty, we have herein provided an intermediate supporting carriage 22 also slidably mounted upon the frame and carrying the head 23 which affords an intermediate journal support for the several separator rods for the harness reed and the warp.

When the machine is to be used for wide work which in practice may run from five to eight feet in extent, the actuating shafts 11 and 12 are preferably provided of an unbroken length extending from the supporting arm 15 of the carriage 5 to the head 17 on the carriage 16,—the intermediate head 23 providing merely a plain journal support for the rods. This condition is represented in Fig. 6, which shows the warp worm shaft 100 11 extending through the auxiliary head 23 and journaled therein. In operating the machine under these conditions, the drawing-in operation is commenced with the carriages 5 and 16 at their starting positions 105 and the carriage 22 closely adjacent the carriage 16. As the drawing-in operation progresses the traversing carriage and the pattern head carriage gradually move to the left (as viewed in Fig. 1), leaving the then 110 stationary intermediate carriage 22 behind. This movement is preferably continued until the advance of the actuating shafts relatively to the head 23 brings the rods at the position which affords the desired support, whereupon the intermediate carriage then and thereafter is caused to be moved and advanced also with the traversing carriage 5. This may be effected by any desired means, but herein we have provided upon the gib 21 120 (see Fig. 14) the stop block 24 to which is secured the plate 25 overlying and adapted to slide upon the upper face of the guile-way afforded by adjacent machine frame, the said block being brought into contact with 125 the near side of the intermediate carriage 22, when it is desired to move the latter with the pattern-head carriage. Obviously the block 24 may be adjusted to various positions lengthwise the gib so that the final position 130

of the intermediate carriage relatively to the pattern-head carriage may be selected at will and to secure the most favorable position for the intermediate carriage dependent on the 5 length of actuating shafts employed.

It will, therefore, be seen that, in the use of this machine with extra wide warps, the pattern-head carriage is preferably started in close proximity to the intermediate carriage and then, after withdrawing from the 10 intermediate carriage for a space dependent on the location of the block 24, is caused to continue its movement with the intermediate carriage also moved therewith.

In order that the described machine may be employed either with extra wide warps or with warps of ordinary width, provision is 15 preferably made whereby the relatively short separator rods, which are customarily used with work of the latter class, can be employed in connection with the auxiliary head, and the length of the traversing unit correspondingly reduced. For this purpose provision is made for receiving the ends of such 20 short rods in the intermediate carriage as they would be received in the head 17 and for coupling them thereto to the pattern-head by short auxiliary shafts 26. This is the condition represented in Figs. 1 and 7 25 where the ends of the rod 11 are shown as entering a socket formed in the coupling 27, which socket is provided with the hinged key 28 adapted to enter a slot 29 in the end of the rod. The key is provided with a latch 30 30 engaging a shoulder in the rod and is normally pressed into engagement therewith by a spring 31, so that the rod, when inserted in the socket, will be held locked therein, but can be removed therefrom by pressing out 35 the latch.

The auxiliary rod 26 which extends to a corresponding coupling on the head 17 is 40 preferably fixedly secured to a collar 32, which abuts against the head of the coupling 27. The collar 32 is provided with one or 45 more pins 33 (herein two) fixed in and extending from its abutting face and registering with members of a series of corresponding holes in the abutting face of the coupling. Herein (see Fig. 15) twelve such 50 holes are employed.

When the machine is assembled with the short and auxiliary shafts, the shaft 26, having been inserted through the head 23, 55 the coupling is applied as shown and a set screw 34 turned up to secure the coupling and the auxiliary shaft against longitudinal withdrawal. The ends of the separator rods can then be inserted in the coupling as desired. The pins 33 with their registering 60 holes in the coupling provide convenient means for securing slight angular adjustment between each separating device and its driving shaft, thereby to adjust or correct 65 the timing of the separator, for, by unloosening

the said screw 34 and withdrawing the coupling the latter with its separator shaft can be turned one-twelfth of a revolution or any multiple thereof and then replaced.

In the described form of machine, when 70 the machine is employed with the short separator shafts and the auxiliary shafts, as described, the intermediate carriage is preferably secured at a fixed distance from the pattern-head carriage 16 and travels 75 therewith at all times as the latter with the traversing carriage moves during the warp-drawing operation. For this purpose any suitable means for thus locating the intermediate carriage relatively to the pattern- 80 head carriage may be employed, but in the described embodiment of our invention we have provided (see Figs. 1 and 13) one or more spring-pressed latch bolts 35 vertically arranged near the edge of the carriage 22 and adapted, when located at the required distance from the pattern-head carriage, to register with and enter a hole formed in the gib 21 connecting the carriages 5 and 16. The bolt 35 is provided 85 with a head 36 by which it can be withdrawn and it also has a laterally extending pin 37 working in a vertical slot 38 so that when raised with the pin 37 above the upper surface of the carriage 22 the bolt can 90 be turned and the pin 37 will hold it against reentrance. The carriage 22 therefore can be either locked to the pattern carriage for use with the short actuating shafts or freed 95 therefrom and employed with the long 100 shafts as previously described.

In warp-drawing machines it is customary to support the reed upon some movable carrier to permit of longitudinal adjustment during the operation of the machine 105 in response to the action of the reed opener or other reed positioning device. This has ordinarily been accomplished by providing a reed carriage of substantially rectangular formation adapted to hold the reed rigidly 110 against vibratory movement as a whole, while permitting the entire carriage to have an adjusting longitudinal movement. While this provides a solid support for the reed, 115 the parts undergoing movement are necessarily heavy and impose considerable work upon the reed opener and the reed splits. This is especially the case where warps of extra widths are to be drawn requiring reeds 120 and reed supporting carriages of greatly increased length and weight.

In the present instance we have provided 125 novel supporting means for the reed intended to afford a sufficiently rigid support for the same to withstand the drawing-in operation while materially reducing the weight of the supporting parts, as well as increasing the facility with which the reed may be connected to and disconnected from 130 and adjusted in the machine.

Referring more particularly to Figs. 2 to 5 and 8 to 12, the reed 4 is sustained at suitably selected points in its length by clamps 39 which depend from the carrier bar 40, the latter in turn being sustained by a plurality of hangers 41, provided each with a roller 42 tracking upon the stationary reed bar or track 43. The latter is held against transverse displacement in vertical 10 guides 44, but may be vertically adjusted by means of end adjusting rods 45 and an intermediate adjusting rod 46, all of which have threaded engagement with the supporting bar 43, so that, when the rods are turned, the latter is raised or lowered.

In the present instance we have provided means for simultaneously turning, not only the end adjusting rods 45, but also the intermediate rod 46, so that the reed bar 43 20 can be adjusted by the operator from one end of the machine. In the present instance this is effected by providing one of the end rods 45 with turning means, such as the knurled hand wheel 47 by which the same 25 may be turned, this acting, through the beveled gearing 48 near the top thereof, to turn the horizontal shaft 49 suitably journaled near the top of the machine framing. The shaft 49, in turn connects with the intermediate adjusting rod 46 by means of beveled gearing 50 and with the remaining end adjusting rod 45 by means of beveled gearing 51, so that, as the hand wheel 47 turns, all 30 three adjusting rods are given a similar and corresponding adjusting movement effecting a uniform raising or lowering of the reed bar and reed.

While support may be provided for the lower bar of the reed throughout all or a 40 large portion of its length, in the present instance we have provided supporting means for a portion of its length only, and have also provided such supporting means upon the traversing carriage 5, whereby it 45 affords support to the reed adjacent the line of needle action and where most needed.

In the present machine this is attained by providing a channel-like support (see Figs. 1, 3 and 4) 52 in which the reed bar can 50 move longitudinally, but is prevented from transverse movement. Such support herein is mounted upon the adjusting arm 15 of the carriage and is held rigidly beneath the reed bar and just below the line of needle action, thereby preventing any transverse vibratory movement of the reed bar at or adjacent the region where engaged by the drawing-in needle. Since the support for the lower reed bar advances with the needle, 55 no reed supporting devices are required for the reed on the reed carrier other than the clamps 39.

Referring to Fig. 9, each reed clamp is 60 provided with jaws 53 and 54 which tightly grip the upper bar of the reed. The two

jaws are pivoted at 55, the jaw 53 having a web projection 56 on which is formed the hub 57 embracing and pinned or otherwise secured to the carrier bar 40. The jaws are forced into gripping engagement with the reed bar by means of the spring 58, which spring, however, can be compressed and the jaws retracted to release the reed bar by means of a releasing plate 59 interposed between the web projection 56 of the jaw 53 and a projection or finger 60 for the jaw 54. To this end the releasing plate 59 (see Fig. 10) where it engages the projection 60 is provided with a beveled edge 61, so that, when moved in the direction of the arrow, 70 it acts as a wedge and forces the finger 60 away from the projection 56 separating the two jaws. The releasing bar extends the entire length of the carrier bar 40 and is operatively related to all the clamps as above 75 described, so that when moved longitudinally, it simultaneously opens all the clamping jaws and releases the reed.

Means are preferably provided for moving the releasing bar from some given point, 80 and for this purpose there is preferably provided (see Figs. 3, 11 and 12) a hand lever 62 which is pivotally mounted to engage a notch 63 in the edge of the releasing bar 59, so that, by movement of the lever about its pivot, the bar may be moved simultaneously 85 to open the clamps. While the lever 62 may be located in any desired position, in the illustrated machine it is pivotally mounted upon a block 64 which is clamped to the carrier bar 40 near its mid-position (see Fig. 3).

In order to prevent swinging movement of the reed clamps the hangers 41 (see Fig. 8) which are pinned or otherwise fixedly secured to the carrier bar 40, are provided not only with the rollers 42 which track with the upper edge of the reed bar 43, but also each with a roller 65 journaled on an upright axis on the hanger and adapted to roll along the lower back face of the reed bar. Co-operating with the roller 65 and a flange 66 on the roller 42, which flange overlaps the outer edge of the reed bar, are smaller rollers 67 secured to the hanger 41 and having 100 rolling contact against the opposite face of the reed bar so that, while free rolling movement of the hanger is permitted lengthwise of the bar 43, the hanger at all times by reason of the rollers 65 and 67 and the flange 66 is held in the desired upright position and acts 105 to hold the reed in rigid alignment without the possibility of swinging or vibratory movement.

While we have herein shown and described, for purposes of illustration, the specific details of one embodiment of our invention, it is to be understood that the same is not limited to the mere details shown, nor is it limited in its application to the particular machine or type of machine wherein the 110

same is herein shown embodied. On the contrary, various applications may be made of the several features of our invention, and extensive modifications may be had in its 5 constructional features without departing from the spirit thereof.

Having thus described our invention, what we claim is:

1. In a machine for separating and selecting warp threads, the combination with 10 separating and selecting mechanism movable relatively to the warp threads, a separator shaft for actuating the same, supports for the opposite ends of the said shaft and movable relatively to the warp threads with 15 the said mechanism, and an intermediate support for the said shaft relative to which said separating mechanism and actuating shaft have a traveling movement.
2. In a machine of the class described, 20 the combination with separating and selecting mechanism, of an actuating shaft therefor, a support for each end of said shaft, and an intermediate support relatively to which said shaft is longitudinally movable 25 during a part of the operation of the machine, but longitudinally fixed for the remaining part of the operation thereof.
3. In a machine of the class described, 30 the combination with a separating and selecting device, an actuating shaft therefor, a support for the end of said shaft, an intermediate support, means for causing the separation of the intermediate and end supports during the first part of the operation 35 of the machine, but for holding them relatively fixed during the remainder of the operation thereof.
4. In a warp drawing machine, the combination with a plurality of separating and 40 selecting devices, actuating shafts therefor, a pattern control head operatively related to said shafts at one end, an intermediate support for said shaft, and means permitting the separation of said pattern head and intermediate support during the first part 45 of the operation of the machine, but for holding the same at a fixed distance relatively thereto during the remaining portion thereof.
5. In a machine of the class described, 50 the combination with a plurality of separating devices, a plurality of actuating shafts therefor, a sliding support for the ends of said shafts, an intermediate relatively movable support, and means for locking the intermediate support to move with the said end support.
6. In a machine of the class described, 60 the combination with a plurality of separating devices, a plurality of actuating shafts therefor, a sliding support for the ends of said shafts and a relatively movable intermediate support therefor.
- 65 7. In a warp drawing machine for wide

warps, the combination with a loom reed carrier, of adjustable end supports for vertically adjusting said carrier, and an intermediate adjustable support also for vertically adjusting said carrier.

8. In a warp drawing machine, the combination with a loom reed carrier, of intermediate and end supports for said carrier, and means for simultaneously adjusting said supports.

9. A warp drawing machine having a loom reed, and separate but interconnected end and intermediate supports for the reed which are capable of simultaneous uniform adjustment.

10. A warp drawing machine having a longitudinally movable reed carrier supporting the reed and attached thereto wholly at the upper rib thereof.

11. A warp drawing machine having a movable reed carrier, traversing mechanism, and means for supporting said reed partly by said carrier and partly by means carried with said traversing mechanism.

12. A warp drawing machine having a movable reed, a reed carrier supporting the reed by its upper rib, and means for supporting the lower rib of the reed adjacent the line of action of the drawing-in needle.

13. A warp drawing machine having a movable reed, a reed carrier supporting the reed by its upper rib, and means relatively movable across the reed with the drawing-in mechanism for supporting the lower rib of the reed adjacent the line of action of the drawing-in needle.

14. In a warp drawing machine, the combination with a loom reed, of a traversing carriage having drawing-in mechanism, and supporting means upon said carriage for engaging the lower rib of the reed.

15. In a warp drawing machine, the combination with a loom reed, drawing-in mechanism, means for causing relative movement between the reed and the drawing-in mechanism, reed supporting means associated with the drawing-in mechanism and movable relatively to the reed with the said mechanism for engaging the lower rib of the reed and preventing transverse movement thereof, while permitting relative longitudinal movement.

16. In a warp-drawing machine, the combination with a plurality of reed carrier clamps, and means for simultaneously releasing the said clamps.

17. In a warp drawing machine, the combination with a plurality of reed carrier clamps, of a releasing member extending longitudinally of said clamps, and means for moving said releasing member to simultaneously open all of said clamps.

18. In a warp-drawing machine, the combination with a plurality of reed carrier clamps having clamping jaws, means for
